CLAIM

The ornamental design for a loudspeaker, as shown and described.

DESCRIPTION

FIG. 1 is a top perspective view of a loudspeaker showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof;

FIG. 7 is a bottom view thereof;

FIG. 8A is a partial enlarged view according to the broken rectangle 8A denoted in FIG. 1, showing that the grille illustrated by stippling in FIGS. 1 and 6 is in solid lines;

FIG. 8B is a partial enlarged view according to the broken rectangle 8B denoted in FIG. 1, showing that the grille illustrated by stippling in FIGS. 1 and 6 is in solid lines;

FIG. 9A is a partial enlarged view according to the broken rectangle 9A denoted in FIG. 1, showing that the grille illustrated by stippling in FIGS. 1 and 6 is in broken lines;

FIG. 9B is a partial enlarged view according to the broken rectangle 9B denoted in FIG. 1, showing that the grille illustrated by stippling in FIGS. 1 and 6 is in broken lines;

FIG. 10A is a partial enlarged view according to the broken rectangle 10A denoted in FIG. 1, showing that the grille illustrated by stippling in FIGS. 1-4 is in broken lines;

FIG. 10B is a partial enlarged view according to the broken rectangle 10B denoted in FIG. 1, showing that the grille illustrated by stippling in FIGS. 1 and 2 is in solid lines; and,

FIG. 10C is a partial enlarged view according to the broken rectangle 10C denoted in FIG. 1, showing that the grille illustrated by stippling in FIGS. 1-3 and 5 is in broken lines.

The evenly spaced broken lines in the figures illustrate portions of the loudspeaker that form no part of the claimed design. The dash-dot broken lines in the figures represent the boundaries of the claimed design and form no part of the design.
